E. P. PETRO,
NEEDLE THREADING DEVICE.
APPLICATION FILED OCT. 13, 1917.

1,278,995.

Patented Sept. 17, 1918.

Elmer P. Petro,

Inventor

By *Lancaster and Alvaro*
his Attorney.

UNITED STATES PATENT OFFICE.

ELMER P. PETRO, OF SYLVAN LAKE, ALBERTA, CANADA.

NEEDLE-THREADING DEVICE.

1,278,995.

Specification of Letters Patent. Patented Sept. 17, 1918.

Application filed October 13, 1917. Serial No. 196,483.

To all whom it may concern:

Be it known that I, ELMER P. PETRO, a subject of the King of Great Britain, and a resident of Sylvan Lake, in the Province of Alberta and Dominion of Canada, have invented a certain new and useful Improvement in Needle-Threading Devices, of which the following is a specification.

The present invention relates to a device for facilitating the threading of needles, and has for an object to provide a support for a magnifying glass which may be held in a hand which simultaneously supports the thread or needle.

The invention further aims at the provision of a device which may be formed upon the handles of a pair of shears in such manner that when the handles of the shears are grasped in the usual manner the device is retained at the desired angle for viewing the eye of the needle and the point of the thread as magnified; and to provide a device which is so mounted upon the handle of the shears as to hold the latter in position when resting on a support for ready insertion of the fingers.

The above, and various other objects and advantages of this invention will be in part described and in part understood, from the following detailed description of the present preferred embodiment, the same being illustrated in the accompanying drawing wherein:

Figure 1 is a perspective view of a device constructed according to the present invention and as applied to one handle of a pair of shears.

Fig. 2 is an edge view of the shears resting on a table or other support, and showing the device of the invention holding the shears in tilted position for easy grasping.

Fig. 3 is a transverse section through the inner end of the shears showing the device attached thereto and holding the shears in raised tilted position.

Referring to this drawing, the invention comprises a frame or rim 10 which may be of circular or other desired configuration, and which supports therein a magnifying lens 11.

The frame 10 may be attached to or integrally formed with the handle A of a pair of shears which, in conjunction with the opposite handle B, is adapted to be grasped by the thumb and fingers of one hand. The handles A and B are adapted to be grasped

in the usual manner for supporting and operating the shears, and when grasped in such manner this holds the rim 10 in position to magnify or enlarge the view of a needle or end of thread which may be held between the thumb and fingers after the latter have been inserted through the loops of the handles A and B.

To facilitate the inspection of the needle C, shown in Fig. 1, and the end or point of the thread D, also shown in Fig. 1, the rim 10 projects at an angle oblique from the plane of the handles A and B, and which inclines toward the free ends of the fingers 70 supporting the handles of the shears. The focal axis of the lens 11 is therefore in direct line with the ends of the thumb and fingers which hold the shears, and when the hand is raised before the face in the usual manner 75 of examining the needle and thread, the lens 11 will be turned and held in the correct position.

The arrangement of the frame or rim 10 at this angle also serves the purpose of holding the shears, when resting upon a table or other support, in partly raised and tilted positions, as shown in Figs. 2 and 3. The finger loops of the handles A and B are therefore held clear of the support and the 85 thumb and fingers may be readily engaged downwardly through the loops without the necessity of first lifting the shears in the other hand and subsequently applying the thumb and fingers of the first hand there- 90 through.

The attachment therefore not only serves to support the shears in position to be readily grasped, but also is held and supported in the correct position for viewing 95 the needle and thread by merely holding the shears in the usual manner.

It is of course understood that various changes and modifications may be made in the details of construction and design of the 100 above specifically described device without departing from the spirit of the invention, and being restricted only by the scope of the following claims.

I claim:

1. The combination with a pair of shears having a pair of handles adapted to be grasped in the hand, of a frame carried upon one of the handles, and a magnifying lens mounted in said frame, said frame extending at an angle to the plane of the handles of the shears sufficient to aline the longi- 110

ludinal focal axis of the lens on an object held between the fingers supporting the shears.

2. The combination with a pair of shears having the usual handles adapted to be grasped by the fingers in the usual manner, of a lens carried by one of the handles and projecting at an angle thereto and adapted

to engage a support for holding the handles in a raised, tilted position for easy grasping 10 when the shears are not in use, the lens being arranged at an angle to also align the longitudinal focal axis of the lens on an object held between the fingers of the hand supporting the shears.

ELMER P. PETRO.
